UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed June 7, 1929. Serial No. 369,094.

My invention relates to a slicing machine and is applicable for example to a slicing machine of a type having a rotary and preferably a motor driven knife. One object of my invention is to provide means for clearing the slices from the knife as they are severed. Another object is to provide support for the front end of the work and for the slice as it is severed. Another object is to insure the delivery of flat and uncurled slices. Another object is the provision of a support for the work and for the slice being severed therefrom which shall be thoroughly effective at the point where the knife engages the work. Another object is the provision of means for keeping the supporting member clear and for discharging the slices therefrom as they are severed. Other objects will appear from time to time in the course of the specification and claims.

I illustrate my invention more or less diagrammatically in the accompanying drawings, wherein—

Figure 1 is a front elevation;

Figure 2 is a corresponding rear elevation;

Figure 3 is an end elevation;

Figure 4 is a section on the line 4—4 of Figure 3;

Figure 5 is a section on the line 5—5 of Figure 4;

Figure 6 is a view similar to Figure 4 from an opposite direction;

Figure 7 is a plan view;

Figure 8 is a section on the line 8—8 of Figure 6;

Figure 9 is a similar section through a modified form;

Figure 10 is a partial side elevation of the structure shown in Figure 9; and

Figure 11 is a section through a variant form.

Like parts are indicated by like symbols throughout the specification and drawings.

A generally indicates a base upon which is mounted a motor not herein shown in detail but concealed beneath the cover or housing member A¹. A² indicates a belt about a driving pulley actuated by the motor.

B indicates a guard plate which is herein

shown as lying in a generally vertical plane, and B¹ indicates a gauge plate. B³ indicates a carrier member for the gauge plate which may be actuated in any suitable manner for example by rotation of the knob B⁴ which is mounted in any suitable manner on the base A. The knob B⁴ is associated with the shaft B⁵ which is held against axial movement in relation to the base A. It may be provided with a worm or screw portion B⁶ in mesh with a correspondingly threaded member diagrammatically indicated as B⁷ on the lower extension B⁸ of the carrier member B³. It will be understood that the carrier member B³ is rotatable about the shaft B⁵ but is normally held against rotation and limited to a sliding movement across the base. In order to effect a tilting adjustment of the member B⁸ and the carrier B³, with the consequent control of the tilt of the lower edge of the gauge plate B¹, I provide bearing blocks B⁹ B¹⁰ on the base the height of which may for example be controlled by the associated screws B¹⁰ and the lock nuts B¹¹. The members B⁹ slidably engage bosses or flat portions of the member B⁸, indicated as B¹² B¹³. It will be understood that rotation of the knob B⁴ and thus of the shaft B⁵ moves the gauge plate and gauge plate assembly toward or away from the cutting plane along an axis co-incident with the axis of the shaft B⁵.

C indicates a knife mounted upon any suitable knife shaft C¹. C² is a pulley associated with the knife and knife shaft, about which passes the belt A², whereby the knife is rotated.

D indicates a circular track and D¹ a guide track therebeneath, herein shown as of rectangular cross-section. The tracks are parallel. Mounted for movement along the track D is the meat carriage generally indicated as D² which includes a generally horizontal upper portion D³ upon which the work support later described rests. Depending from the carriage D² is the portion D⁴ which is provided with a plurality of downwardly depending lugs D⁵ positioned one on each side of the track D¹. These lugs are provided with adjusting members or screws D⁶ with their

lock nuts D⁷, whereby a certain range of adjustment is allowed, having for effect to tilt the carriage D² about the track D.

Pivoted to the carriage D² is a flat work supporting plate generally indicated as E. It is secured for example upon the supporting member or members E¹ associated with the hinge or hinges E² which are aligned with the pivot lugs E³ upon the carriage D². E⁴ indicate any suitable pivot pins whereby the parts are mounted in pivotal relation. The member E when in its lowest position lies in a generally horizontal plane, as shown in Figure 1. I provide a slight adjustment of its level, as for example the member E⁵ which is screwthreaded in the top of the carriage D² and which may be locked at any set position, as by the nut E⁶. The member E may be held at any desired position of adjustment, as by the links E⁷ slotted as at E⁸, and engaged by the locking member or knob E⁹. E¹⁰ indicates a flange along the edge of the plate E and E¹¹ E¹² are guards associated with said flange.

In order to provide a support for the work and for the slices as they are being severed from the work, which shall be constant, regardless of the position of the gauge plate, I provide a work supporting bar or shelf, generally indicated as G, as for example in Figures 2 and 3, which is supported on the base or frame and which is shown as underlying the gauge plate and the gauge plate support. It is preferably provided, as shown in Figure 8 and in the variant form of Figure 9, with a terminal portion G¹ which lies adjacent the knife edge and conforms to the rear face of the knife adjacent and within said edge, and closely approaches it. In effect the knife edge is positioned in the recess G² and the form of this recess or cut away portion is such that the support extends forwardly of the cutting plane of the knife edge. This is clearly shown in Figures 8 and 9. Therefore the support G extends across the cutting plane, lying in part on each side thereof. The cut away portion G² is formed as at G³ in Figure 6 arcuately to conform to the curvature and be capable of arrangement closely adjacent the knife edge.

It will be seen, as in Figures 5, 8 and 9 that the edge of the work support E is spaced somewhat back from the cutting plane, but closely approaches the opposed edge of the member G. Since the member G hugs the knife edge the work, as it approaches the cutting edge, is supported both by the plate E and by the member G until the severance of the slice is actually begun. The severed portion of a partially severed slice is supported upon the terminal portion G¹ of the member G. I find that in order to prevent material falling on the member G¹ and to prevent any gathering of material between it and the knife and between it and the frame

or housing, it is advantageous to provide a terminal fillet at the end of the member G¹. In Figure 8 I indicate this fillet G⁵ as formed on the frame. In the variant form of Figure 9 I indicate a recess in the frame, as at G⁶, the fillet being formed as at G⁷ at the top of the member G¹ penetrating the recess G⁸ in the rear face of the knife.

Since one of the objects of my invention is to provide a constant support for the work, I find it desirable to maintain the gap between the members G and E as narrow as possible, at least in handling relatively plastic or soft material, such as meat. I therefore provide means for adjusting the relationship between the members G and E. In the form of Figures 4 and 5 I illustrate adjusting apertures H in the frame through which pass adjusting screws H¹ of considerably smaller diameter than the apertures H. These screws penetrate the member G as at H² and are provided with a head H³, whereby they may be drawn up into locking or holding position. The relative size of the screws H¹ and the apertures H permits adjustment of the bar G longitudinally toward and away from the knife edge and transversely toward and away from the edge of the member E. It may be desirable to affect also a vertical adjustment, in which case I may provide for example the shims H⁴ shown in Figure 11. In Figure 11 I show the shim H⁴ only about the adjusting screw nearest the knife edge but I wish it to be understood that I may employ the shim with either or both adjusting screws, depending upon the kind and degree of adjustment desired. For example by putting a shim about a screw nearest the cutting edge of the knife only I lift the inner end of the member or bar G. Under some circumstances I find it desirable to have the inner end of the bar higher than the rest of the bar. If this is not desired, the bar may be vertically adjusted as a whole by employing shims at both ends of the bar.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In slicing machines of the type in which a rotary knife is employed and a work supporting carriage is guided across the face of the knife, I have in the past employed a gauge plate which is moved toward and away from the cutting plane. The edge of the carriage closest the cutting plane is normally constantly positioned. That is to say,

while there may be a certain adjustment possible by rotating the carriage about the circular track D, such an adjustment cannot practically be made at every movement of the gauge plate, and the adjustment is limited by the cutting plane, since the carriage cannot be moved into the cutting plane and still perform its conveying function across the face of the knife. The gauge plate, however, 5 may be withdrawn a very substantial distance to the rear of the cutting plane and if a thick slice is being cut the end of the work which is being sliced projects outwardly beyond the support afforded by the carriage 10 and, if soft material is being sliced, the work may sag and depend and is without the support which I find to be necessary for clean and accurate slicing. In order to bridge the gap between the normally fixed carriage and the constantly adjusted gauge plate I provide the slice support generally indicated as G, which underlies the gauge plate and which supports that portion of the work which extends toward the gauge plate beyond the edge 15 of the carriage. In practice I find this support extremely important and it is particularly important that this support be adequate at the point where the cutting edge of the knife actually penetrates the work. 20 It will be observed for example, as in Figures 4, 6 and 10 that I provide an upwardly inclined portion at the end of the member G closest the cutting edge. Referring for example to Figures 4 and 6 I illustrate the 25 member G as having a generally plane upper surface G¹⁰ which may be for example, at the level of the bottoms of the corrugations G¹¹. At the end of the member G, however, I provide an upper level portion 30 G¹², which may be connected with the plane of G¹⁰ as by the incline G¹³. I may dispense, however, as shown in Figure 10, with the plane support G¹², or rather, I may terminate the upper level G¹² at or within the cutting edge of the knife, as shown in Figure 35 10 and the incline G¹³, in such case, lifts the edge of the work upwardly at the end of its excursion toward the cutting edge of the knife. Whereas I do not wish to be limited 40 to any specific dimensions, I find it desirable in many cases to have the plane G¹² or the upper portion of the incline G¹³ lie in substantially the level of the tops of the corrugations as shown in Figure 5, the lower level 45 G¹⁰ being thereby positioned below the tops of the corrugations. The corrugations, whether they are along the edge of the support E, or whether, as may be desirable, they extend entirely across the face thereof, are thus permitted to exercise their function, 50 thruout the major portion of the member G, which is to prevent drawing back or frictional distortion of the work by engagement with the member G or the gauge plate. In 55 employing a corrugated carriage any tend-

ency of the work to slip back from the knife is thus minimized and the work is soundly supported and firmly urged against the cutting edge. The result is the practical elimination of tailing and frictional distortion of the work but also a very substantial reduction of larding, which is caused by the frictional engagement of the distorted work with the rapidly moving knife. In general practice the objectionable phenomena of tailing and larding go together and by firmly urging the work toward the cutting edge both are greatly reduced. That is to say, I prevent or greatly limit tailing and larding by providing adequate support for the material being sliced, which support prevents recession of the material from the knife or dragging or thrusting back of the front face or edge of the material in relation to the mass of the material, as it engages the knife. The result of the employment of my structure is the provision of a firm support back of the cutting plane, at the point of cutting and the firm application of driving force against the material. The flange E¹⁰ and the guard E¹¹ also aid in this firm support of the work, since they abut against the side of the work opposite to the cutting edge of the knife and prevent rearward movement of the work away from the knife and frictional dragging of the work along the gauge plate. Finally, the upward inclination or the upward adjustment of the end of the member G, where the work actually engages the cutting edge of the knife gives a maximum of support at the cutting point. The member G at that point may be even with the tops of the corrugations and the work, and the slice as it is being severed from the work, rests firmly upon the plane surfaced top of the member G at that point. 95

The portion G¹ of the member G conforms closely to the rear of the knife and has to some extent the function of a scraper. The member G is preferably so adjusted to the knife as well as being shaped to conform to it, that no room is left for slices or for bits of meat and the like of any substantial size to penetrate between the knife and the support. In order to prevent jamming or packing of material at this point I find it highly desirable to employ a fillet at the end of the support G. This fillet may be formed upon the frame or guard portion of the machine, as shown in Figures 4 and 11 as at G⁵, or it may be formed on the member G itself, as shown at G⁷ in Figures 9 and 10. In the former case the fillet is preferably recessed below the level of the upper portion of the member G, this recessing being clearly shown in Figure 11. 100

It is important that the support G be properly adjusted and adjustable in relation to the gauge plate and the carriage and the knife. The securing screws H¹ in the aper-

tures H, as shown in Figures 4, 5 and 11 for example, permit of longitudinal adjustment of the member G toward and away from the cutting edge of the knife. They also permit of transverse adjustment of the member G toward and away from the carriage. These adjustments are preferably made at the factory but they are sufficiently simple and easy to enable the ordinary operator to make them himself if need be. A close approach of the member G to the carriage or supporting member E being important I may obtain this adjustment by moving the member G toward and away from the carriage edge. I may also control the relationship of the carriage edge to the member G by rotating the carriage about the track D, as by employment of the adjusting members D⁶ and the locking screws D⁷, as shown in Figure 3. If this rotation of the carriage is sufficient to affect the height of the carriage edge, then the member G may be vertically adjusted, as by employment of shims such as H⁴.

A further adjustment which may be necessary is the adjustment between the upper face of the member G and the lower edge of the gauge plate. The gauge plate B¹ is preferably adjusted upon a support B³ as by the screws B¹⁵. As above pointed out the member G can be vertically adjusted and its inclination can be adjusted by employment of shims H⁴ at either or both ends. Finally, the gauge plate and its support can be tilted as a unit, as by actuation of the supporting members B⁹. Note also that the inclination of the member E may be adjusted as by actuation of the adjusting or supporting member E⁵ shown in Figure 1. The member E⁵ controls the level of the support E when it is in its lowest position, limiting its rotation about its pivot toward the surface of the carriage member proper D². I wish it understood that all of these various adjustments may be employed in a single machine if found desirable and equally that in practice I may dispense with some of them.

It will therefore be seen that I have insured, by the various adjustments above described, the ability of the operator to maintain the necessary close contacts or approaches between support and knife, between support and gauge plate and between support and carriage.

I claim:

1. In a slicing machine having a rotary knife and means for rotating it, a carriage and means for guiding it across the plane of the knife, a gauge plate lying in a plane generally parallel with the path of movement of said carriage and means for moving it toward and away from said carriage and a work supporting member underlying said gauge plate and extending along the path of movement of said carriage and lying on each side of the cutting plane of the knife, said work

supporting member being mounted independently of the gauge plate, and means for tiltably adjusting the lower edge of the gauge plate in relation to the upper face of said work supporting member.

2. In a slicing machine having a rotary knife and means for rotating it, a carriage and means for guiding it across the plane of the knife, a gauge plate lying in a plane generally parallel with the path of movement of said carriage and means for moving it toward and away from said carriage and a work supporting member extending along the path of movement of said carriage and lying on each side of the cutting plane of the knife, said work supporting member being mounted independently of the gauge plate, and means for vertically and independently adjusting the opposite ends of said work support.

3. In a slicing machine having a rotary knife and means for rotating it, a work carriage and means for guiding said carriage across the face and past the cutting arc of the knife, a work supporting member lying in the general horizontal plane of the carriage, extending adjacent the cutting edge of the knife, the upper face of said work supporting member adjacent the cutting edge of the knife being higher than the upper face of the work supporting member more remote from the cutting edge, a portion of the face of the work supporting member adjacent the cutting edge of the knife being upwardly inclined toward said cutting edge.

4. In a slicing machine having a rotary knife and means for rotating it, a guard plate positioned forwardly of said knife, a gauge plate and means for maintaining it at all positions in general parallelism with the guard plate, a work carriage and means for guiding said carriage across the face and past the cutting arc of the knife, the forward edge of said carriage being in general parallelism with, but spaced somewhat away from the faces of the guard plate and gauge plate, a normally fixed work supporting means lying in the general horizontal plane of the carriage, and underlying the lower edge of the gauge plate, and extending on both sides of the cutting plane of the knife, one portion of said work supporting means conforming closely to the rear face of the peripheral portion of the knife, the portion of the supporting means which projects forwardly of the cutting plane terminating adjacent to but exteriorly of the periphery of the knife, the outer edge of the supporting means being parallel with and closely adjacent to the opposed edge of the carriage said work supporting means extending substantially from edge to edge of the gauge plate and being positioned, throughout its length, in close proximity to the forward edge of the car-

riage, in a plane forwardly of the cutting plane parallelism with the opposed edge of the carriage.

5. In a slicing machine having a rotary knife and means for rotating it, a guard plate positioned forwardly of said knife, a gauge plate and means for maintaining it at all positions in general parallelism with the guard plate, a work carriage and means for guiding said carriage across the face and past the cutting arc of the knife, the forward edge of said carriage being in general parallelism with, but spaced somewhat away from the faces of the guard plate and gauge plate, a normally fixed work supporting means lying in the general horizontal plane of the carriage, and underlying the lower edge of the gauge plate, and extending on both sides of the cutting plane of the knife, said work supporting member being mounted independently of the gauge plate and means for longitudinally adjusting it in relation to the cutting edge of the knife and means for transversely adjusting it in relation to the opposed knife face and the opposed edge of the carriage, said work supporting member lying closely adjacent to and in general parallelism with the opposed edge of the carriage said work supporting means extending substantially from edge to edge of the gauge plate and being positioned, throughout its length, in close proximity to the forward edge of the carriage, in a plane forwardly of the cutting plane.

6. The construction of claim 5 characterized by the further provision of means for vertically adjusting the work supporting member in relation to the lower overlying edge of the carriage plate.

7. In a slicing machine having a rotary knife and means for rotating it, said knife being mounted for axial removal, a guard plate positioned forwardly of said knife, a gauge plate and means for maintaining it at all positions in general parallelism with the guard plate, a work carriage and means for guiding said carriage across the face and past the cutting arc of the knife, the forward edge of said carriage being in general parallelism with, but spaced somewhat away from the faces of the guard plate and gauge plate, a normally fixed work supporting means lying in the general horizontal plane of the carriage, and underlying the lower edge of the gauge plate, and extending on both sides of the cutting plane of the knife, said work supporting member being mounted independently of the gauge plate and means for vertically adjusting it in relation to the overlying lower edge of the gauge plate and the adjacent edge of the carriage, and means for transversely adjusting it in relation to the opposed knife face and the opposed edge of the carriage, said work supporting member lying closely adjacent to and in general

Signed at Indianapolis, county of Marion and State of Indiana, this 3rd day of June, 1929.
